UNITED STATES PATENT OFFICE

JÖRGEN JACOBSEN MÖLLER, OF FLENSBURG, GERMANY.

HYDRAULIC SEAL OR TRAP FOR JARS, &c.

SPECIFICATION forming part of Letters Patent No. 643,230, dated February 13, 1900.

Application filed December 12, 1899. Serial No. 740,090. (No model.)

To all whom it may concern:

Be it known that I, JÖRGEN JACOBSEN MÖLLER, a subject of the King of Prussia, German Emperor, and a resident of Flensburg, in the Province of Schleswig-Holstein, in the Kingdom of Prussia, German Empire, have invented certain new and useful Improvements in Hydraulic Seals or Traps for Jars and Similar Receptacles, of which the following is a specification.

The present invention relates to the closing of jars and similar receptacles for preserving and conserving objects of any kind, particularly food, fruits, and the like, and has for its object the providing of an improved hydraulic seal or trap-like joint between the jar and its cover or lid. This improved seal or trap mainly consists of an outer oil seal and an inner fluid seal of a vaporizable antiseptic liquid, both seals being combined and arranged in such a manner that the closing of the jar is rendered absolutely air-tight, protecting the contents from access of oxygen and consequent fermentation and conserving at the same time the said contents by permanently keeping them under the influence of the antiseptic vapors of the said vaporizable antiseptic liquid, which vapors have free access to the interior of the jar, but are protected from escaping into the atmosphere by the oil seal.

With this end in view my invention consists in certain novel features of construction and combination of parts, as will be hereinafter fully described with reference to the accompanying drawing, on which I have shown in vertical section a double-sealed jar made in accordance with my invention.

The jar or receptacle *a* is provided, preferably on its outer surface and near its top, with an upwardly-bent flange *b*. The basin formed by this flange and surrounding the jar proper is divided by an intermediate flange or partition *c* into two chambers or troughs. The outer chamber or trough *b'* is filled or nearly filled with a liquid of an indifferent nature, such as oil or the like, while the inner chamber or trough *b''* contains an antiseptic vaporizable substance or liquid—such as a solution of formaline, acetic acid, and the like—capable of volatilizing at ordinary temperatures and forming thereby antiseptic vapors.

The cover or lid *d* of the jar has the form of an inverted double-rimmed cup, the rims *d'* and *d''* of this cup being of such form and arrangement that when the cover *d* has been placed in the proper position upon the jar they descend or enter into the corresponding chambers *b'* and *b''* and are submerged into the oil or antiseptic liquid, respectively, contained therein, as will be clear from the drawings without any further explanation.

As the cover *d* does not rest upon the wall proper of the jar, the antiseptic vapors formed by the vaporizing antiseptic liquid in the chamber *b''* are free to enter into the interior of the jar and to annihilate or destroy any septical germs or septic which may have been passed into the jar when placing the contents in it or when putting the cover *d* upon the jar. These vapors will also act upon the contents themselves as a conservative means, as germs or septic contained in or on the said contents will be annihilated by the said antiseptic vapors. From escaping into the atmosphere the said antiseptic vapors are protected by the oil seal in the outer trough *b'*.

In some cases it may be expedient to have the contents to be preserved and conserved placed in a separate receptacle *a'*. This receptacle may then be inserted into the jar *a*, as shown in the drawing, and may also be closed by a separate cover *e*, which, however, must leave sufficient free space or passage between itself and the top rim of the receptacle *a'* in order to allow the antiseptic vapors to pass through such passage into the interior of the receptacle *a'*, for which purpose short radial ridges or spacing-lugs *o* are provided on the under side of the lid-seat. The sunk top room of the preferably-cup-shaped cover *e* may also be filled, if desired, with a vaporizing antiseptic means, as indicated in the drawing.

Having fully described my said invention, I declare that what I claim, and desire to secure by Letters Patent, is—

1. In a jar, a rim provided with a pair of channels, a lid, a pair of depending flanges thereon the outer longer than the inner, adapted to take into said channels, an internal receiver suspended in said jar from a peripheral flange, a lid for said internal receiver, spacing-lugs thereon and a depression in said

lid for the reception of an antiseptic, substantially as set forth.

2. In a jar or similar receptacle the combination of two chambers or troughs $b' b^2$ attached to the jar and surrounding each other, the inner trough being filled with a vaporizing antiseptic means and the outer trough with an indifferent liquid, and of a cover provided with two flanges or rims $d' d^2$ corresponding to the troughs $b' b^2$ and adapted to enter the latter, a free passage being left between the cover and jar, substantially as and for the purpose specified.

3. In a jar, a rim provided with channels for containing vaporizable chemical preservatives and a liquid seal, a lid provided with depending flanges, the outer one of which supports the lid and rests on the bottom of its

channel, an internal receiver adapted to hang from the interior wall of said jar, and an auxiliary lid for covering the internal receiver, as set forth.

4. In a jar, a rim provided with channels, a lid having depending flanges adapted to take into said channels and be liquid-sealed, an internal receiver provided with a flange and hung therefrom in said jar, a lid for said receiver, a closing-rim having spacing-ribs, and a depression in said lid for the reception of a vaporizable preservative, substantially as set forth.

JÖRGEN JACOBSEN MÖLLER.
